UNITED STATES PATENT OFFICE.

YUSKE MIYASAKI, OF MCKEES ROCKS, PENNSYLVANIA.

TRUCK-BOLSTER.

1,091,375.

Specification of Letters Patent. Patented Mar. 24, 1914.

Application filed October 15, 1913. Serial No. 795,317.

To all whom it may concern:

Be it known that I, YUSKE MIYASAKI, a subject of the Emperor of Japan, residing at McKees Rocks, in the county of Allegheny and State of Pennsylvania, have invented certain new and useful Improvements in Truck-Bolsters, of which the following is a specification, reference being had to the accompanying drawings.

10 This invention relates to new and useful improvements in cast steel truck bolsters for railway cars and the primary object of the invention is to provide a highly efficient bolster which will be free from shrinkage strains and common defects.

15 A further object of the invention resides in providing a truck bolster of the character described in which a uniform thickness of metal is maintained throughout the section 20 and a proper distribution of the metal made throughout.

25 Still another object of the invention resides in providing double flanges at the top and bottom of the bolster so arranged as to 30 present the most economical section possible which is capable of dealing with the forces met therewith in practice.

35 A still further and more specific object of the invention is to provide a device which is simple and durable in construction, inexpensive to manufacture and one which will be very efficient and useful in operation.

40 With these and other objects in view, the invention consists in the novel features of 35 construction, combination and arrangement of parts as will be hereinafter referred to and more particularly pointed out in the specification and claims.

45 In the accompanying drawing forming a 40 part of this application, Figure 1 is a plan view of my device. Fig. 2 is a front elevation thereof. Fig. 3 is a section as seen on line 3—3, of Fig. 2; and Fig. 4 is a similar view as seen on line 4—4, of Fig. 2.

50 In describing my invention, I shall refer 45 to the drawing in which similar reference characters designate corresponding parts throughout the several views and in which 1 indicates a flat metal section designed to 55 form a web, the same being increased in height from points adjacent each end, toward the center thereof, as indicated at 2 and formed on the upper and lower edges of said web section, are the T-head flanges 3 and 4, respectively. These upper and 60 lower flanges 3 and 4 on the web section are

equal in width for the greater portion of their length and the same terminate in widened or increased portions 5, affording increased bearing surfaces at such points and 60 said flanges 3 and 4 are provided with enlarged openings 6 on each side of the web section at the increased or widened end portions 5 thereof.

65 The upper and lower flanges are connected together at the end portions 5 thereof, by means of the vertical walls 7, which are cast integral therewith and extend to points just beyond the junction of the increased or widened portions 5 of the flanges 70 with the remaining portions thereof and the outer faces of these side walls are provided with pairs of spaced apart ribs 8, providing means thereon for the reception of beams or other engaging members. Also formed integral with the upper face of the upper flange 3, at points adjacent and inward from the openings 6 therein, are the upstanding flanges 9 which are designed to inclose 75 rectangular spaces, said flanges being provided 80 for obvious purposes.

85 The web section 1, at the central portion thereof has a substantially vertical tubular portion 10 formed therein, which tubular portion is tapered larger toward its upper end and terminates at its upper end in a reduced opening. The bore at the lower end of said tubular portion also terminates in a reduced opening in the bottom flange 90 of the device. Surrounding the opening in the top flange 3, is an annular flange 11 and also formed on the top face of said top flange 3, is an additional annular flange 12 which is of a diameter equal to the width of the top flange 3, at the center thereof. The 95 provision of this latter flange on the device provides substantially a bowl-like member for a center plate support.

100 Formed integral with the faces of the web section 1, below and above, respectively, the upper and lower flanges 3 and 4, are the additional upper and lower laterally extending flanges 13 and 14, respectively. These flanges, at the central portion of the device are of slightly less width than the 105 flanges 3 and 4 and the same taper somewhat toward their outer ends, as can be clearly seen from the dotted lines shown in Fig. 1 of the drawing and said flanges are braced to the web section 1, by means 110 of the integral brace flanges or the like 15. These flanges 13 and 14 are arranged paral-

lel to the flanges 3 and 4 and the upper additional flange 13 is additionally braced by means of the additional brace flanges which are formed integral with the inner faces of the wall of the tubular member 10 and also integral with the under face of the upper additional flange 13, the same extending radially inward toward the center of the bowl-like member.

10 The central portion of a bolster of this character receives the greatest strain, as is well known and in order to aid this portion of my improved bolster to withstand the strain and shock received at this point, T-shaped supporting or bracing flanges 17 are formed between the upper and lower flanges 3 and 13, at the point at which this substantial bowl-shaped member is formed. The shank portions of these substantial T-shaped bracing or supporting flanges extend inwardly toward the center of the device, as can be seen in dotted lines in Fig. 1, while the head portions thereof are somewhat arcuately designed and arranged somewhat 20 in circular alinement. Each head portion is spaced slightly from the other, as can be seen from Fig. 2 of the drawing and the same aline with the annular flange 12, as clearly shown in the section indicated as 30 Fig. 3 of the drawing. These flanges 17 are, as are all the other portions of the device, cast integral with the flanges.

It must be here stated that the web and the flanges of the device are made of uniform thickness and this uniformity of metal insures a sound casting throughout, which is capable of withstanding the many shocks and strains received in practice and reduces the shrinkage strain to a minimum. It also 35 provides a bolster which attains the greatest strength to withstand greater bending stress and shock than a bolster of disproportionate thickness. A bolster constructed in this manner also avoids the drawing of the 40 metal which is at present necessary in the construction of bolsters of this character.

By providing the double flanges, as shown and described, at the top and bottom of the web of the bolster, a greater moment of inertia is obtained without constructing said 50 flanges of greater thickness than the web, within a limited depth of section. It will also be seen that the flange 13 increases the moment of inertia at the center of the bolster 55 and also acts as a center plate support, being reinforced by flanges 16, thereby permitting this bowl-shaped portion of the device to be made uniform in thickness with the other portions of the device and avoid 60 drawing of the metal and shrinkage strain at the vital point of the bolster.

From the foregoing it will be seen that I have provided a simple, inexpensive and efficient means for carrying out the objects of 65 the invention, and while I have particularly

described the elements best adapted to perform the functions set forth, it is obvious that various changes in form, proportion and in the minor details of construction may be resorted to without departing from the 70 spirit or sacrificing any of the principles of the invention.

Having thus described this invention, what I claim is:—

1. A cast truck bolster consisting of a web, 75 lateral flanges formed on the upper and lower edges thereof, additional upper and lower lateral flanges formed on said web and spaced slightly from the aforesaid flanges to form pairs of parallel flanges, and connecting means between the first mentioned upper and lower flanges at the ends thereof.

2. A cast truck bolster comprising a web, lateral flanges formed on the upper and lower edges thereof and extending the full 85 length of the same, and additional upper and lower lateral flanges formed on said web in spaced relation to the aforesaid flanges, said additional flanges being of less length and of less width than the first mentioned flanges and tapering smaller toward 90 their outer ends.

3. A cast truck bolster comprising a web, flanges formed on the upper and lower edges thereof, extending the full length of the 95 same, side walls connecting said flanges at the outer ends thereof, and additional upper and lower flanges formed on the web in spaced relation to the aforesaid flanges, and terminating slightly in advance of the inner 100 opposed ends of said side walls.

4. A cast truck bolster comprising a central web, flanges formed on the upper and lower edges thereof and extending the full length of the same, additional flanges 105 formed on said web in spaced relation to the aforesaid flanges, bracing webs formed between the central web and the last mentioned flanges, and additional bracing means formed between the central portions of the 110 upper flanges of the device.

5. A cast truck bolster comprising a central web having a tubular portion formed centrally thereof, flanges formed on the upper and lower edges of said web having the 115 terminal openings of said tubular portion therein, an annular flange immediately surrounding the tubular opening in the upper flange of the web, an additional annular flange formed on said upper flange to surround the first mentioned annular flange and form a substantial bowl-like member on the upper flange of the device, and bracing means for the central portion of the upper flange on the web.

6. A cast truck bolster comprising a central web having a tubular portion formed centrally thereof, flanges formed on the upper edges of said web and having the terminal openings of said tubular portion therein, 130

additional upper and lower flanges formed on said web in spaced relation to the aforesaid flanges, annular flanges formed on the top face of the flange on the upper edge of 5 the web and forming a bowl-like member thereon, bracing means formed between the upper flanges of the web to brace the aforesaid bowl-like member, and additional bracing means formed between the additional flanges and said central web.

7. A cast truck bolster comprising a web, lateral flanges formed on the upper and lower edges thereof and extending the full length of the same, pairs of additional laterally extending flanges formed on the web in slightly spaced relation to the aforesaid flanges and parallel thereto, said last mentioned flanges terminating some distance in 15

advance of the ends of the web, a tubular member formed centrally of said web and 20 having the ends thereof terminating in openings in the first mentioned upper and lower flanges, substantial T-shaped bracing members formed between the upper parallel flanges on said web, additional bracing 25 means formed between the additional flanges and said web, and annular flanges formed on the top of the upper of the first mentioned flanges on the web to form substantially a bowl-shaped member thereon. 30

In testimony whereof I hereunto affix my signature in the presence of two witnesses.

YUSKE MIYASAKI.
